CLAIM

The ornamental design for a juicing machine, as shown and described.

DESCRIPTION

FIG. 1 is a front end view of a new design for a juicing machine;

FIG. 2 is a right side view thereof;

FIG. 3 is a front perspective view thereof;

FIG. 4 is a back perspective view thereof;

FIG. 5 is a back view thereof;

FIG. 6 is a top view thereof; and,

FIG. 7 is a bottom view thereof.

The broken lines showing the logos Zumex and Soul are for illustrative purposes only and form no part of the claimed design.
